UNITED STATES PATENT OFFICE.

PAUL EUGENE GERHARD, OF LEBANON, PENNSYLVANIA, ASSIGNEE TO LEBANON STEEL FOUNDRY, OF LEBANON, PENNSYLVANIA, A CORPORATION OF PENNSYLVANIA.

FLANGeway AND RAILWAY-RAIL GUARD STRUCTURE.

Application filed December 23, 1927. Serial No. 242,057.

This invention relates to flangeway and railway rail guard structures and is in the nature of an improvement on the invention set forth in my Patent No. 1,645,279 of October 11, 1927; and in my Patent No. 1,659,730, granted February 21, 1928, for flangeway and rail guards for highway crossings of railroads.

The objects of this invention are to interlock the meeting or abutting ends of aligned guard sections of the class mentioned where the meeting ends come opposite, that is, above, cross ties; and also when they do not come opposite or above cross ties, in such wise as to hold the interlocked section firmly in working position.

In the accompanying drawings forming a part hereof and illustrating the best form of my invention now known to me;

Fig. 1 is a side elevation of two aligned endwise contacting guard sections. The view shows a T-shaped opening at the meeting ends of the sections and also a similar opening wholly enclosed by the web of a section.

Fig. 2 is a perspective view showing endwise abutting, aligned guard sections one at one side and the other at the other side of a railway track rail, two T-shaped openings being wholly enclosed by the guard webs and one of the openings being at the meeting ends of the sections; the latter opening having positioned in it an interlocking device which is the head of a brace leading to a cross tie under the meeting ends of the sections. The sections at the right hand side of the track rail are portions of flangeway guard sections, and the sections at the left hand side of the track rail are track rail guard sections.

Fig. 3 is a perspective view similar to Fig. 2 but shows a brace head in an opening above the cross tie with the brace secured at its lower end to the cross tie. The view also shows the shankless head or locking device in an opening spaced apart from the cross tie.

Fig. 4 is a perspective view of the shankless head of locking device shown in Fig. 3; and Fig. 5 is a perspective view of the head having an integral shank as illustrated in Figs. 2 and 3.

In laying or installing both the flangeway guards and the track rail guards it frequently happens that the meeting or abutting ends of the sections do not come to-

gether over a cross tie but spacedly apart therefrom between adjacent ties. The present invention is intended for the production of these sections in such wise that their meeting ends can be interlocked whether such meeting ends are over cross ties or are between cross ties.

In the drawings, 1 is a track rail shown in place on a cross tie 3. A indicates a section-
alized flangeway guard adjacent and spaced
apart from the inward side of the track
rail, the sections being in endwise alignment
and having their opposed ends in contact.
B indicates a track rail guard adjacent but
spaced apart from the outward side of the
track rail. The space 5^a between the track
rail and flangeway guard is for reception of
paving material but this space 5^a is not to
be completely filled with paving material
which is placed in the space so as to come
only part way up to the tops of the rail and
flangeway guard for entrance of a wheel
flange as set forth in my said patent applica-
tion, which also shows the present space 5^b
between the track rail and the track rail
guard filled with paving material up to the
tops of the track rail and track rail guard.
The top of the rail and the tops of the
guards at each side are approximately flush
one with another in actual installations.

In accordance with the present invention,
webs 10 of the guard sections are respec-
tively provided at desired intervals apart
along the lengths of the sections, between
the ends of the sections, with one or more
T-shaped openings T each wholly enclosed
by the metal of a web 10.

At their meeting ends each section web
is formed with an inverted L-shaped open-
ing in its margin (Fig. 1) and when the
two inverted L-shaped openings are opposed
one to the other, the two L-shaped openings
form a T-shaped opening T' as shown in
Fig. 1. The downward extension of these
T-shaped openings is indicated by T². In
Fig. 5 I show a bracing and web interlock-
ing device, its head comprising a neck 20
from each side of which a pair of cross arms
18 extend, one on one side and the other on
the other side of the neck, in opposite di-
rections. From each side of the neck, at
its outward end, another pair of cross arms
18^a severally project in opposite directions,
there being a preferably, outwardly flared
space between each cross arm 18 and a later-

ally opposed cross arm 18^a. The spaces between the laterally opposed cross arms severally receive a margin of the wall of a downward extension T² when the parts are 5 assembled; each of the cross arms 18 then bearing on a surface 10^a of the web adjacent the downward extension T² and each of the cross arms 18^a then bearing on a corresponding surface of the web opposed to a surface 10 indicated by 10^a. The neck 20 enters the downward extension T² below the upper transverse portion of the T-shaped opening. The shank of the bracing and locking device is indicated by 19, its base 19^a being spiked 15 to a cross tie.

When the meeting ends of sections come 20 between cross ties the shank 19 is unnecessary and the four-armed head of the shank with its neck 20 is used for interlocking the meeting ends of the sections. The cross armed head is dimensioned; or, at least, its outermost arms 18^a and neck 20 are dimensioned, to pass into and through the upper transverse portion of each T-shaped opening; and 25 then the neck is forced down into an extension T² with the side margins of the downward extension forced in place each between two opposed cross arms 18 and 18^a. The inward tapers of the spaces between each 30 two of the laterally opposed cross arms 18 and 18^a permit each pair of laterally opposed cross arms to come into tight gripping relations with the two opposite web surfaces at 10^a.

35 The meeting ends of the webs are thus tightly interlocked by the two cross arms bearing on the outward, and by the two cross arms bearing on the inward side of, a web, portions of each web being anchored 40 in a space between two laterally opposed cross arms. The result is to prevent lateral displacement of one web in relation to the other; to endwise connect the meeting ends of two sections, and practically to prevent 45 vertical displacement of one section in relation to the other.

Various shapes of the openings and various shapes of the shankless interlocking device, or head of the bracing shank, may be 50 devised other than as shown, without departure from this invention, the function of which is to grip the section webs on their opposite sides between opposed bearing surfaces of the head or locking device, whether it has, or does not have, a shank for connection with some stationary element of the track structure.

What I claim is:

1. In flangeway and track rail guard structure, the combination of a guard web 60 provided with an opening for reception of a web locking device; and a web locking device having a neck and at each end thereof, rigid, opposingly projecting, laterally spaced apart, web engaging members; the wall of said opening and said device being dimensioned for assemblage, and in assemblage, the neck passing through a portion of the opening with surfaces of two of said spaced apart members bearing on one side, 70 and surfaces of two other spaced apart members bearing on the other side, of the web.

2. In flangeway and track rail guard structure, the combination of a guard web provided with an opening for reception of a web locking device; and a web locking device having a neck and at each end thereof, rigid, opposingly projecting, laterally spaced apart, web engaging members; the wall of said opening and said device being dimensioned for assemblage, and in assemblage, the neck passing through a portion of the opening with surfaces of two of said spaced apart members bearing on one side, 80 and surfaces of two other spaced apart members bearing on the other side, of the web; said locking device having a shank; and a track element to which the shank is fixed.

Signed at Lebanon in the county of Lebanon and State of Pennsylvania this 26 day 90 of November A. D. 1927.

PAUL EUGENE GERHARD.
